BUFFING OR POLISHING MACHINE

Francis W. Lovett, Hatfield, Mass., assignor to
Porter McLeod Machine Tool Co. Inc., Hatfield,
Mass., a corporation of Massachusetts

Application February 14, 1931. Serial No. 515,739

6 Claims. (Cl. 51—84)

This invention relates to machines for buffing and polishing cutlery and the like.

It has for its object the provision of a device of this character which shall be more efficient in operation than those previously used and capable of imparting a mirror-like finish to such metals as stainless steel.

Other and further objects will become apparent from the following specification and claims.

10 In the accompanying drawings, which illustrate one embodiment of this invention:

Fig. 1 is a plan view;

Fig. 2 is a front elevation;

Fig. 3 is a section on line 3—3 of Fig. 4;

15 Fig. 4 is a section on line 4—4 of Fig. 1;

Fig. 5 is a side elevation, taken from the left of Fig. 1;

Fig. 6 is a detail view showing the construction of the polishing rolls;

20 Fig. 7 is a detail view showing the means for adjusting the polishing rolls;

Fig. 8 is a detail plan view of the work holder, parts being broken away; and

25 Fig. 9 is an end elevation of the structure shown in Fig. 8.

Referring to the drawings, the machine, in brief, comprises a casing 1 upon which are supported parallel, independently driven buffing or polishing rolls 2 and 3, and a slide 4 mounted for reciprocation transverse to the rolls 2 and 3. A second slide 6 which carries the work support 8 is mounted on slide 4 for reciprocation parallel to rolls 2 and 3. The work support is preferably made adjustable on the slide 6 as shown. Means, later to be described, are provided for simultaneously reciprocating slides 4 and 6, with the result that as the work is moved back and forth in the bite of the rolls by the reciprocation of slide 4 they are also and with a greater frequency moved sidewise by the reciprocation of slide 6.

30 The shaft 10 of roll 2 is journaled in the free ends of arms 11 and 12 splined or otherwise secured to a rocker shaft 13 mounted in upright bearing members 14 secured to the top of casing 1 by bolts 15. Pads 19 of rubber or other suitable material are interposed between members 14 and the casing to eliminate vibration. Arm 12 is extended, as best shown in Fig. 1, to form a bracket 16 to which an electric motor 17 is secured by bolts 18, the shaft of the motor forming an extension of, or being directly connected to, the shaft 10 of the roll.

35 Similarly the shaft 20 of roll 3 is journaled in the free ends of arms 21 and 22 splined or other-

wise secured to a rocker shaft 23 mounted below shaft 13 in the bearing members 14. Arm 21 is extended to form a bracket 25 to which an electric motor 26 is secured by bolts 27, the shaft of motor 26 forming an extension of, or being 60 directly connected to, shaft 20 of roll 3.

It will thus be seen that each roll 2 and 3 is independently driven by its motor and at full motor speed.

45 Shafts 13 and 23 are adapted to be simultaneously rocked in opposite directions by means of a turn buckle 29, the oppositely threaded ends of which engage in nuts 30 and 31 pivoted respectively in the free ends of arms 32 and 33 which are splined respectively to shafts 13 and 23. As 70 best shown in Fig. 7, shafts 13 and 23 are geared together as by segmental gears 34 and 35 respectively secured to said shafts so that rotation of turnbuckle 29 operates to simultaneously rock shafts 13 and 23 in equal amounts but in opposite directions, thus swinging rolls 2 and 3 toward or from each other to adjust their spacing for work of different thickness at the same time keeping constant the central plane of the bite of the rolls, in which the work is moved by slides 4 and 6. Because of the geared connection of shafts 13 and 23, rolls 2 and 3 and their associated parts and motors tend to balance each other.

50 Slide 4 is mounted for reciprocation on a dovetailed guide 36 (see Fig. 2) formed on the top of casing 1, and is provided with a pin 37 extending downwardly through a slot 38 into the casing. Slide 6 is mounted for reciprocation on a dovetailed guide 40 (see Fig. 5) formed on slide 4 and is provided at one end with a pin 41 extending 75 downwardly into the casing through an arcuate slot 42.

55 The slides 4 and 6 are driven from a horizontal shaft 44 journaled in bearings 45 and 46 (see Figs. 3 and 4) formed in the ends of casing 1. Shaft 44 is driven from a motor 47, supported in the casing by a bracket 48, by means of a sprocket chain 49. A worm 50 secured on shaft 44 meshes with a worm gear 51 secured to a vertical shaft 52 journaled in a thrust bearing 53 formed in a 100 bottom web 54 and a bearing 55 formed in a bracket 56 projecting from the end of the casing. Vertical shaft 52 carries at its upper end a crank 58 connected to an arm 59 by a link 60. Arm 59 is split, as best shown in Fig. 4, to receive a bearing 61 formed on the end of link 60 and is slotted as at 62 to receive a stub shaft 63 passing through bearing 61 and held in adjusted position in slots 62 by means of a nut 65. Arm 59 is pivoted at one end to a stud 66 projecting downward- 105

55 110

ly from the top of the casing and its free end is connected to pin 37 of slide 4 by link 59'. As will be clear from Fig. 3 and the foregoing description, adjustment of stub shaft 63 in slots 62 will 5 vary the amplitude of the reciprocation imparted to pin 37 and slide 4 by rotation of crank 58 without changing its frequency or graduation.

Vertical shaft 52 is provided intermediate its ends with a large gear 67 which meshes with a 10 small gear 68 secured to a vertical shaft 69 journaled in bracket 56. Vertical shaft 69 is provided on its upper end with a crank 70 connected by a link 71 to one end of a lever 72. Lever 72 is pivoted intermediate its ends on a stud 73 secured to 15 the under side of the top plate of casing 1 and its other end is connected by a bent link 74 to pin 41 of slide 6.

It will thus be seen that while the slides are reciprocated simultaneously from horizontal shaft 20 44, the frequency of reciprocation of slide 6 (due to gearing 67—68) is several times that of slide 4. Furthermore, due to the adverse leverage of lever 72, the amplitude of movement of slide 6 is substantially less than that of slide 4. The amplitude 25 of the reciprocations of slides 4 and 6 are respectively indicated in Fig. 3 by double headed arrows *a* and *b*, and it will be noted that the stub shaft 63 is set to give very nearly the minimum travel to slide 4.

30 As shown in Figs. 2 and 3, horizontal web 54 is downwardly inclined forwardly and toward the center and with vertical webs 75 and 76 form an oil pan 77 which keeps shaft 44 and the gearing carried thereby constantly lubricated. A drain plug 78 is provided at the lowest point of web 54. Preferably anti-friction bearings are used 35 throughout the assembly.

The work support is carried by slide 6 and comprises vertical posts 80 adapted to receive work 40 holding clamps such as shown at 81 (see Fig. 8). In the drawings, the clamp consists of a lower bar 82 provided with grooves 83 in which the handle ends of knife blades 84 are somewhat loosely positioned on pins 85. An upper bar 86 loosely 45 clamps the blade handles against the lower bar by means of a wing nut 87, the articles having only enough freedom of movement so that they can contact uniformly with the rolls. The bars 82 and 86 are provided adjacent their ends with 50 apertures 88 adapted to seat on the upper ends of posts 80. It will be understood that the clamping bars 82 and 86 may take varying forms depending on the kind of work to be buffed or polished. As is obvious, by the arrangement shown 55 the blades are simultaneously polished on both sides, but if desired an article may be mounted on the holder to contact with but one roll to polish or buff a single surface.

The polishing rolls 2 and 3 are formed of disks 60 of felt 90 (see Fig. 6) spaced apart by fiber disks 91 of less diameter than disks 90, the disks 90 and 91 being held tightly together on the roll shaft by nuts 93.

65 By making the frequency of reciprocation of one slide greater than the other, the paths of reciprocation are made to shift with respect to each other, and if the frequencies are made other than a multiple of each other this shift varies with each reciprocation until the slides again complete a reciprocation at the same time, when the cycle is 70 repeated. For example, if slide 4 is given 8 1/2 reciprocations per minute, while 45 reciprocations per minute are imparted to slide 6, the path of reciprocation of slide 6 shifts constantly back and forth lengthwise of the rolls in a path generally 75 indicated by the curvature of slot 42. Since these frequencies are other than multiples of each other, the shift is not constantly along any one curve but follows a series of varying arcuate paths within slot 42 through a cycle of five reciprocations of slide 4 when both slides will complete their reciprocation at the same time. The cycle is then repeated.

80 As will be obvious from the foregoing, the knife blades or other work carried by the work support will be reciprocated in the bite of the rapidly rotating rolls 2 and 3 by the reciprocation of slide 4, which reciprocation may be adjusted to the length of the work, and that simultaneously a constantly shifting, short, quick reciprocation parallel to the rolls is imparted to the work by slide 6. Turnbuckle 29 permits a nice adjustment of the 85 bite of the polishing rolls and the pressure exerted on the work by the felt disks.

90 The invention is not limited, of course, to double roll machines but may, if desired, be applied to devices having a single roll or other type of buffer.

95 What I claim is:

1. A buffing and polishing machine which 100 comprises a casing, a pair of rolls mounted thereon, an electric motor connected to the shaft of each roll to drive it independently of the other, means to simultaneously move the rolls toward and from each other to adjust their spacing to various thicknesses of work, a slide mounted on 105 said casing for reciprocations in directions transverse to the axes of the rolls, a second slide mounted thereon for reciprocations in directions parallel to the axes of the rolls, a work support carried by the second slide, a horizontal shaft 110 positioned within the casing, means to drive said shaft, a vertical shaft geared to the horizontal shaft, a crank secured to the vertical shaft and operatively connected to the first slide, said connection being adjustable to vary the amplitude 115 of the reciprocation imparted to the slide by said crank, a second vertical shaft, gearing connecting said vertical shafts and adapted to drive the second shaft at a greater or less speed than the first shaft, and a crank secured to the second 120 shaft and operatively connected to the second slide.

2. A buffing and polishing machine which 125 comprises a pair of buffing and polishing rolls of greater length than the width of the work pieces to be polished, means to drive said rolls, a slide mounted for reciprocations in directions transverse to the axes of the rolls, a second slide mounted on the first slide for reciprocations in directions parallel to the axes of the rolls, a work 130 support carried by the second slide, means to repeatedly reciprocate the first named slide to pass the work back and forth through the bite of the polishing rolls and means to simultaneously and repeatedly reciprocate the second named slide 135 to move the work to and fro sidewise in the bite of the rolls with a frequency greater than and other than an integral multiple of the frequency of reciprocation of the first named slide.

3. A buffing and polishing machine which 140 comprises a pair of buffing and polishing rolls of greater length than the width of the work pieces to be polished, means to drive said rolls, a slide mounted for reciprocations in directions transverse to the axes of the rolls, a second slide 145 mounted on the first slide for reciprocation in directions parallel to the axes of the rolls, a work support carried by the second slide, means to repeatedly reciprocate the first named slide to pass the work back and forth through the 150

- 5 bite of the polishing rolls and means to simultaneously and repeatedly reciprocate the second named slide to move the work to and fro sidewise in the bite of the rolls, the path of each successive to and fro reciprocation being longitudinally and laterally offset from the one immediately preceding, the relative frequencies of the reciprocations imparted to said slides being such as to cause the said offset paths to follow 10 a different course for each of a succeeding series of half reciprocation of the first named slide.
- 10 4. A buffing and polishing machine which comprises a pair of buffing and polishing rolls, a slide mounted for reciprocations in directions transverse to the axes of the rolls, a second slide mounted on the first slide for reciprocations in directions parallel to the axes of the rolls, a work support carried by the second slide, means to repeatedly reciprocate the first slide to pass 15 the work pieces back and forth through the bite of the rolls, means to adjust the amplitude of the reciprocations imparted to the first slide, without changing the frequency of the reciprocations, to thereby accommodate work pieces of 20 different length, means to simultaneously and repeatedly reciprocate the second slide to move the work to and fro sidewise in the bite of the rolls and means to simultaneously and repeatedly reciprocate the second slide to move the work to and 25 fro sidewise in the bite of the rolls, with a frequency greater than the frequency of reciprocation of the first named slide.
- 25 5. A buffing and polishing machine which comprises a casing, a pair of buffing and polishing rolls of greater length than the width of the work pieces to be polished, a slide mounted on said casing for reciprocations in directions trans- 30 verse to the axes of the rolls, a second slide mounted on the first slide for reciprocations 35
- 5 bite of the polishing rolls and means to simultaneously and repeatedly reciprocate the second named slide to move the work to and fro sidewise in the bite of the rolls, the path of each successive to and fro reciprocation being longitudinally and laterally offset from the one immediately preceding, the relative frequencies of the reciprocations imparted to said slides being such as to cause the said offset paths to follow 10 a different course for each of a succeeding series of half reciprocation of the first named slide.
- 10 4. A buffing and polishing machine which comprises a casing, a pair of rolls mounted thereon, means to drive each roll independently of the other, means to simultaneously move the rolls toward and from each other to adjust their spacing to various thicknesses of work, a slide mounted on said casing for reciprocations in 15 directions transverse to the axes of the rolls, a second slide mounted on the first slide for reciprocations in directions transverse to the direction of the movement of the first slide, a work support carried by the first slide, means to reciprocate the first slide to repeatedly pass the work back and forth through the bite of the rolls and means to simultaneously and repeatedly reciprocate the second slide to move the work to and 20 fro sidewise in the bite of the rolls and means to adjust the amplitude of the reciprocations of the first slide without changing the relation between the frequencies of the reciprocations of the two slides.
- 20 6. A buffing and polishing machine which comprises a casing, a pair of rolls mounted thereon, means to drive each roll independently of the other, means to simultaneously move the rolls toward and from each other to adjust their spacing to various thicknesses of work, a slide mounted on said casing for reciprocations in 25 directions transverse to the axes of the rolls, a second slide mounted on the first slide for reciprocations in directions transverse to the direction of the movement of the first slide, a work support carried by the first slide, means to reciprocate the first slide to repeatedly pass the work back and forth through the bite of the rolls and means to simultaneously and repeatedly reciprocate the second slide to move the work to and 30 fro sidewise in the bite of the rolls and means to adjust the amplitude of the reciprocations of the first slide without changing the relation between the frequencies of the reciprocations of the two slides.
- 30 7. A buffing and polishing machine which comprises a casing, a pair of buffing and polishing rolls of greater length than the width of the work pieces to be polished, a slide mounted on said casing for reciprocations in directions trans- 35 verse to the axes of the rolls, a second slide mounted on the first slide for reciprocations
